DESIGN FOR A LOCK NUT

James Russell Allen, Forest Hills, N. Y., assignor
to Simmonds Aerocessories Incorporated of
New York, New York, N. Y., a corporation of
New York

Application November 13, 1943, Serial No. 111,690

Term of patent 14 years

(Cl. D54—9)

To all whom it may concern:

Be it known that I, James Russell Allen, a citizen of the United States, residing at Forest Hills, in the county of Queens and State of New York, have invented a new, original, and ornamental Design for Lock Nut, of which the following is a specification, reference being had to the accompanying drawings, forming part thereof, wherein:

Fig. 1 is a plan view of a nut having attached thereto, a lock nut embodying features of my new design;

Fig. 2 is a side elevation of the nut shown in Fig. 1, and

Fig. 3 is an exploded vertical sectional view, taken on line 3—3 of Fig. 2.

The essential feature of my design resides in the specific configurations embodied in the crown or locking element.

I claim:

The ornamental design for a lock nut, as shown and described.

JAMES RUSSELL ALLEN.
